DATA TRANSCEIVER

Paul H. Butler, Barry E. Duggan, and James S. Koonce,
Huntsville, Ala., assignors to Credex Corporation

Filed June 3, 1970, Ser. No. 23,295

Term of patent 14 years

Int. Cl. D14—02

U.S. Cl. D26—5

FIG. 1

FIG. 2

FIG. 1 is a left side perspective view of a data transceiver, showing our design in which a movable carriage which moves between inner and outer positions is in an outer position; and

FIG. 2 is a left side perspective view of the data transceiver shown in FIG. 1 in which the movable carriage is in inner position.

The side and back are plain and unornamented.

We claim:

The ornamental design for a data transceiver, substantially as shown and described.
